UNITED STATES PATENT OFFICE.

ADNAH McMURTRIE, OF NEW YORK, N. Y., ASSIGNOR TO THOMAS & BETTS COMPANY, OF NEW YORK, N. Y., A CORPORATION OF NEW YORK.

MACHINE FOR FORMING SPIRAL TUBING.

1,117,686.

Specification of Letters Patent.

Patented Nov. 17, 1914.

Application filed October 1, 1910. Serial No. 584,925.

To all whom it may concern:

Be it known that I, ADNAH McMURTRIE, of New York, N. Y., have invented certain Improvements in Machines for Forming Spiral Tubing, of which the following description, in connection with the accompanying drawings, is a specification, like references on the drawings designating like parts.

This invention relates to a machine for forming spiral tubing, and is of particular utility when employed in apparatus for manufacture of the helically coiled metal strip used as a protective armor sheath for insulated electrical conductors, although I contemplate the use of my improvements in any field to which they are adapted by their nature.

An important object of my invention is to provide apparatus for a more gradual helical deformation of the somewhat resilient metal strip of which such sheaths are usually formed, than has been customary in coiling such articles heretofore, and accordingly I contemplate the treatment of the strip by forming the convolutions primarily of greater diameter than that of the finished tube, and thereafter reducing gradually but steadily, without undue prolongation of the treatment, the diameter of the convolutions to the desired size.

Another important object of my invention is to accomplish in a unitary operation with the aforesaid helical shaping of the tube, the lateral deformation of the strip along the axis of the helix, which is ordinarily accomplished by treatment of the strip in a separate machine preliminary to the coiling operation, in order to impart to the strip the lateral curvature which has usually constituted the preparation of the strip for its helical formation. My invention utilizes a straight strip instead of a laterally curved strip, in the helix coiling machine.

Armor strips at the present time are of substantial width and thickness owing to the requirements of the fire underwriters and building authorities, and the exigencies of modern building, which make it necessary that the armor shall so far as possible be capable of resisting puncture by nails and other destructive agencies, and such a substantial armor strip is difficult to deform laterally, especially when the strip is of a more or less acutely bent cross section for

purposes of causing interlocking of the convolutions in their helical form, these difficulties militating strongly against a ready reduction of the strip to final spiral form during the formation of the first convolution, as has been the practice heretofore in the manufacture of such armor sheaths.

Any suitable device may be adopted to carry my invention into effect, and as the preferred form of such device I may employ an apparatus comprising rolls presenting working surfaces for engagement with the strip at an angle to the axis of the helix of its formation, the angular relation being secured as desired and found suitable in various situations, as for example, by using substantially straight rolls set at an angle to the axis of the helix, and farther away from said axis at the initial point of convolution, or point of entrance of the strip, than at the region of exit of the finished article.

The various features of my invention will be illustrated and described fully in the accompanying drawings and specification and pointed out in claims.

In the drawings, Figure 1 is a view in front elevation of the preferred form of apparatus for carrying my invention into effect, and in the construction of which my improvements have been embodied; Fig. 2 is a conventional section taken on the line x^2-x of Fig. 1; and Fig. 3 is a fragmentary view similar to Fig. 2, showing in vertical longitudinal section a modified form of roll for use in my improved machine; while Fig. 4 is a sectional view of a suitable strip for treatment.

In the embodiment of my invention selected for illustration and description to permit a ready and complete understanding of the preferred manner in which my invention may be carried into effect, the part designated by the reference numeral 201 is a device for deforming the strip 205 constituting the stock under treatment to form a flexible metallic armor tube in the instance illustrated, and the device itself may be of any suitable character and material to accomplish the desired result.

In accordance with my invention the device acts upon the strip near its point of entry and at a suitable distance from the helical axis, this distance being greater than the radius of the completed sheath, and in the instance illustrated this purpose is served.

by utilizing for the deformation of the strip helically, a roll 201 of tapered periphery, mounted rotatably in bearing members 208 and 209, which in the instance illustrated, extend upward from a suitable support or base 210, with which these standards may be integral, as in the case of the standard 209, or may be separate as in the case of the standard 208, suitable fastening means such as the bolts 212 being provided to secure the standards in place, where required. The number of these rolls may be varied as desired and found suitable to the exigencies of the work on hand; thus I have shown four rolls bearing the reference numerals 201, 202, 203 and 204 respectively, each with an arbor 207 having its axis inclined to the common central axis of the machine, along which the helix is to be formed, and the face of the standard 208 is preferably constructed with its respective portions as right angles to the axes of the rolls. I prefer also to provide the apparatus with means to drive these rolls positively, for which purpose I have shown the arbors 207 as extended beyond the bearing standard 209, and provided respectively with pinions 213, keyed at 214 to their arbors respectively, and meshing with a gear 215 secured by key 216 upon a hollow shaft 217, also journaled in the frame upright 209, this shaft being provided with suitable means such as the gear 218 keyed thereto at 219 to permit the shaft to be driven from a suitable source of power (not shown).

I have shown a bearing standard 221 bolted at 212 to the base 210 and affording a bearing for the hollow shaft 217, the face of the standard being preferably dished in order that this standard may be utilized as a thrust bearing for the arbors 207.

When it is desired to form the sheath 225 in place upon an insulated conductor such as that shown at 226, the latter may be introduced to the sheath through the axial bore of the shaft 217, and the insulated conductor will preferably, but not necessarily, be rotated with the shaft 217 and sheath 225 during the formation of the latter, but inasmuch as such insulated conductors are ordinarily of non-circular contour as illustrated, the sheath need not fit thereupon with greater closeness than will constitute an easy slip fit, the conductor performing no specific function in the formation of the convolutions of the sheath, as will be readily understood by reference to Fig. 2 of the drawings.

The relatively large distance between the rolls at their ends adjacent to the region of entrance of the strip 205, and the correspondingly large diameter of the first convolution, renders its lateral deformation easy, so that the helical lay is imparted with least resistance on the part of the strip owing to the elimination of much of the radial resistance

to bending, and when the first convolution has been made the subsequent reduction of the diameter of the helix is accomplished by successive circumferential bending strains and by increasing lateral deformation.

In the preferred form of machine illustrated in Fig. 2, the hollow shaft terminates outside of the region of operation of the rolls, but I may provide a mandrel of suitable length, and of any suitable construction and arrangement, as for example, by providing the hollow shaft 217 with an integral extension 277, which may be formed tapered as illustrated by the dotted lines in Fig. 2.

In Fig. 3 I have shown a modified form of roll comprising a sleeve 301 secured by a key 306 upon an arbor 307.

I have shown in Fig. 4 in cross section one convenient form of strip 205 for use in the manufacture of helical sheaths, but I do not limit myself to any particular cross section of strip for this purpose.

In the operation of my improved apparatus, the rolls 201, 202, 203, 204 being rotated by actuation of gears 213 through the medium of gear 215 upon the hollow shaft 217, which is driven by the gear 218 actuated in turn from a suitable source of power (not shown), act upon the strip 205 fed thereto in the usual manner from the side, and the strip being engaged with the initial convolution, say of the roll 202 in the lower left hand position illustrated in Fig. 2, and thereafter engaged with a groove upon the roll 203 which is set slightly in advance of the position of the initial groove in roll 202, and similarly when the strip 205 passes to grooves on the rolls 204 and 201 successively, the respectively advanced position of these grooves develops helical deformation of the strip, and feeds it forward into engagement with successive grooves, which operate in turn to feed forward the helical tube thus formed, the rolls serving by their angular disposition to form said helix in progressively decreasing convolutions.

I do not claim herein specifically certain features of construction which form the subject matter of the claims in my co-pending applications Serial Nos. 584,923; 584,924; 584,926 and 584,927.

Having illustrated and described my invention thus fully, and suitable means by which it may be carried into effect, I wish it to be understood that I do not limit myself to the specific construction and materials shown and described by way of example, nor do I limit myself in general otherwise than as set forth in the claims read in connection with this specification.

What I claim as new and desire to secure by Letters Patent of the United States of America is:—

1. Coiling apparatus; comprising a set of rolls rotatable respectively about axes angularly

larly disposed relatively to a common central axis, said rolls having forming-surfaces constructed and arranged to deform a strip helically, and approaching said axis in the direction of formation of said helix to form said helix in progressively decreasing convolutions.

2. Coiling apparatus; comprising a set of rolls rotatable respectively about axes angularly disposed relatively to a common central axis, said rolls having forming-surfaces constructed and arranged to deform a strip helically, and approaching said axis in the direction of formation of said helix to form said helix in progressively decreasing convolutions; and a hollow shaft connected with and to actuate said rolls, and through which an insulated conductor may be led into the sheath constituted by said helix.
- 10 3. Coiling apparatus; comprising a set of rolls rotatable respectively about axes angularly disposed relatively to a common central axis, said rolls having forming-surfaces constructed and arranged to deform a strip helically, and approaching said axis in the direction of formation of said helix to form said helix in progressively decreasing convolutions; and a hollow shaft connected with and to actuate said rolls, and through which an insulated conductor may be led into the sheath constituted by said helix.
- 15 20 3. Coiling apparatus; comprising a set of

rolls rotatable respectively about axes angularly disposed relatively to a common central axis, said rolls having forming-surfaces constructed and arranged to deform a strip helically, and approaching said axis in the direction of formation of said helix to form said helix in progressively decreasing convolutions; and a hollow shaft connected with and to actuate said rolls, and through which an insulated conductor may be led into the sheath constituted by said helix, said shaft having a tapered forepart to serve as a mandrel.

Signed at New York in the county and State of New York this 26th day of Septem-
ber, 1910.

ADNAH MCMURTRIE.
